Patented Apr. 23, 1918.

UNITED STATES PATENT OFFICE.

YORKE BURGESS, OF CHICAGO, ILLINOIS, ASSIGNOR TO AMERICAN SIGNAL COMPANY,
OF KANSAS CITY, MISSOURI.

RAILROAD BLOCK-SIGNALING MEANS.

1,263,371.

Specification of Letters Patent. Patented Apr. 23, 1918.

Application filed January 15, 1917. Serial No. 142,392.

To all whom it may concern:

Be it known that I, YORKE BURGESS, a citizen of the United States, residing at Chicago, in the county of Cook and State of Illinois, have invented certain new and useful Improvements in Railroad Block-Signaling Means, of which the following is a specification.

My invention relates to improvements in railroad block signaling means and has among its general objects to provide a system employing signaling appliances mounted on the cab of the traveling locomotive for communication of information to the engineer; to provide a normally-closed-circuit system; to provide a system in which the track contact devices that are arranged for co-operation with the cab-circuit connections may be made physically a part of the track-rail proper, so as to dispense with a third rail or other extraneous contact devices.

Many other and further objects of my invention will become apparent to those skilled in the art from the following description and appended claims, taken in conjunction with the accompanying drawings, wherein I have illustrated diagrammatically the devices and circuit connections constituting one embodiment of my invention as applied to a double track railway, and showing the association of the cab signal system with the track in various operating conditions.

In the drawing 10 indicates in general a fragment of a double track system whereof 10^e represents an "east bound" track, 10^w a "west bound" track, and 10^s a switch track. In each track, 11 and 12 represent companion rails that also constitute, in part, conductors of the track circuit system. The track is divided into blocks A, B, C, etc., by insertion of insulating bodies 13 in the rail 12 which, for distinction, I designate the "blocked" rail. The other rail 11, which I term for distinction the "continuous" rail is so electrically constituted and equipped as to provide continuous electrical connections from block to block. In one rail, as 11, are provided insulated "control contacts" that are excluded from the track circuit and are intended for inclusion in circuit with instrumentalities, carried by the engine-cab, as hereafter described, the electrical continuity of the rail 11 being maintained by the

provision of a "jumper" 14 around each such insulated control contact.

Each block is provided with an electric track-circuit coextensive with the block, each such track circuit comprising a low voltage battery 15 bridged across the rails at one end of the block, (the "leaving" end, or end more remote in the direction of travel, in the specific illustration) and a track relay 16 having its magnet 16^a bridged by wires 17 and 18 between the rails 11 and 12, respectively, at the other, or "receiving" end of the block.

For the control contact of each block I provide electrical connectors, relay-controlled to connect such contacts with or disconnect them from the continuous rail of the track, such connectors for the contacts appurtenant to each block being governed by the track relay of some other block or blocks.

Thus, specifically, in connection with the selected rail 11, (although either rail will serve) I provide "danger" contacts 20^d and "caution" contacts 20^c for co-operation with moving contacts carried by the train. These track contacts I prefer shall be installed as a physical part of the track rail itself, although electrically they are insulated from that rail and, in some of the aspects of my invention they may be considered as independent of, and parallel to, the rail.

Each track relay 16 controls the electrical connection for some of the danger and caution contacts of more or less remote blocks. In the particular construction shown each relay armature 16^a is shown as a switch tongue, connected as at 22, with the wire 17 leading to the continuous rail 11, such switch tongue playing between two front contacts and a back contact. One of the two front contacts forms the terminal of the wire 23, leading back, (or counter to the direction of travel), along the next adjoining block and connected to a suitable plurality of insulated danger contacts 20^d, two contacts being shown respectively near the "leading" and "leaving" ends of that block. The remaining front contact has a wire connection 24 extending in the same direction, preferably to the caution contact 20^c of the block next adjoining and also to a caution contact 20^c preferably near the leaving end of the second block back from the relay. The back

contact of the relay is connected with this wire 24 by a branch 25 including a resistance element 26.

With the arrangement thus far described, under the normal condition of the track circuit for each block the track relay thereof is energized, and the consequent closure of its armature-switch 16^a against the front contacts affords electrical connection between the respective danger and caution contacts governed by said relay and the continuous rail 11. Thus each appurtenant "danger" contact 20^a has connections 23, 16^a, 22 and 17 to the continuous rail 11 and each "caution" contact 20^c has kindred connections 24, 16^a, 22 and 17 to said rail 11. When the track relay is deenergized for any reason, whether by the breaking of a rail, the opening of some track-switch the closure of which is requisite to maintenance of the electrical continuity of either rail (as at 10^a), or because of the short circuiting of the track circuit by the presence of a train in the block, (the wheels of which train bridge the rails 11 and 12), the consequent deenergization of the track relay and retraction of its armature 16^a breaks the connection for the "danger" control contacts affected thereby and introduces the resistance 26 in the appropriate caution control connections affected thereby.

On the cab of each locomotive I provide, for the engineer's guidance, a set of signal appliances responsive to conditions of the track-contact connections to set various signals. The cab devices comprise a main circuit, governed as to its continuity by the control-contact connections of the track apparatus; and, further, signal circuits affected by the conditions in the main circuit, a brake-controlling circuit also affected by the conditions of the main circuit, and a release circuit for modifying the automatic operation of the brake controlling devices.

Referring to the lower right hand diagram, showing the leading east bound train, that is running under normal or "clear" signal conditions, 30 indicates in general a train 31 being a pair of wheels electrically connected by an axle, and 32 being an insulated wheel constituting a rolling contact for coaction with the track contacts. Of course if the track contacts are placed parallel with the rail instead of included therein, the part 32 would be any suitably disposed traveling contact on the cab. Between wheels 31 and 32 is connected a main circuit that is dependent for its continuity upon the connection between the two wheels afforded by the track. 33 indicates a generator, preferably compound wound, shown as having a shunt field winding 34 of relatively high resistance and a series field winding 35 that connects with a wire 36 leading to wheel 31 and constituting part of

the main circuit. From the other wheel contact 32 wire 37 leads back to the remaining pole of the dynamo through multiple branches 38 and 39 respectively including "danger" magnet 40 and "caution" magnet 41, each said magnet having its other terminal connected to a front contact for its respective armature 40' or 41' and said armatures being connected in common by branch wires 43 and 44 with the remaining terminal of the generator. The magnets 40 and 41 are so wound and spring adjusted, and the field windings of the generator are so proportioned, that the current required to hold the armature of magnet 41 attracted must be greater than that requisite to maintain the magnet 40 effectively energized to hold its armature in attracted position; and the resistance element 26, associated with each caution control contact, is so proportioned that, when included in series with the series field winding 35 of the generator and consequently decreasing the strength of the field, it cuts down the generator voltage to a point where the current is insufficient to maintain "caution" magnet 41 effectively magnetized, though sufficient effectively to magnetize "danger" magnet 40. In consequence of the stated proportioning it will be apparent that as long as the wheels 31 and 32 have low-resistance connection therebetween, both magnets 40 and 41 are effectively energized; that when a resistance 26 is included in the connection between the wheels 31 and 32 "danger" magnet 40 remains effectively energized but "caution" magnet 41 becomes effectively deenergized, and that upon complete rupture of the electrical connections between wheels 31 and 32 both magnets 40 and 41 become deenergized.

The first mentioned condition (that with low resistance connection between wheels 31 and 32) is a normal running condition of the circuit; the second mentioned condition (with a resistance 26 between wheels 31 and 32) is that which exists whenever a "caution" signal is called for by the condition of the track devices; and the third condition (rupture of the cab circuit between wheels 31 and 32) is that encountered whenever a "danger" signal is called for.

To signalize the respective existence of the stated conditions three lamps are provided as convenient annunciators, these being a green lamp 50 to indicate "clear," a yellow lamp 51 to indicate "caution" and a red lamp 52 to indicate "danger." A wire 53 from the appropriate terminal of the generator serves, in common, one terminal of each of the lamps and connects with a brake-magnet 54. The armature of this brake magnet controls the air brakes, supplementally to the usual manual control, so that whenever the armature is retracted the

brakes are automatically set. From the other terminal of this magnet 54 a wire 55 runs to one of the front contacts of danger magnet 40, and in switch-controlled parallel 5 with the brake magnets is disposed a magnet 56 that has an armature 56'. "Clear" lamp 50 has its remaining terminal connected at 57 direct to the front contact of armature 41' for caution magnet 41; "caution" lamp 52 has its remaining terminal 10 connected at 58 to a front contact of armature 56' which in turn is connected by wire 58' with the back contact for armature 41' of the "caution" relay. "Danger" lamp 52 has its remaining terminal 15 connected by wire 59 with the back contact for armature 40' of danger magnet 40. A connection 60 runs from wire 43 to the bottom contact of a manually operable "proceed" switch 61, the tongue of which 20 is connected with wire 55, forming, with respect to the brake magnet circuit a normally open jumper around the armature switch 40' so that when the "proceed" switch tongue is depressed it affords a closed circuit for 25 the brake magnet notwithstanding that the normal brake-magnet circuit may be broken at armature 40'. The top, normally closed contact of said "proceed" switch connects with wire 62 that includes magnet 56 and 30 lead to wire 53; so that closure of the proceed switch opens the circuit for magnet 56, which normally is in direct parallel with brake-magnet 54.

Several operating conditions are shown in 35 the drawings. The leading east-bound train has a clear track ahead. All of the control contacts in its block, D, are electrically connected with the continuous rail. Consequently whenever the train may be within 40 that block, whether with its wheel 32 on a control contact or not, the main cab circuit is closed via 33, 35, 36, 31, rail 11 (or low resistance connections between control contacts and said rail 11), 32, 37, branches 38, 45 40, 40', 43 and 39, 41, 41', 44, 33. Thus as shown by the heavy line circuit "clear" signal-lamp 50 is energized by connections 33, 44, 41', 57, 50, 53, 33 while the brake magnet 54 also is energized through the circuit 33, 50 43, 40', 55, 54, 53, 33, and the brake applying armature is held in normal, non-operating position. The west bound train is displaying a "caution" signal. Owing to the opening of the siding switch illustrated at S, 55 which, if so desired, may be built to rupture the track circuit when so opened, and also because of the presence of a car in the siding in such position that it does not clear the track (shown by the fact that its wheels are 60 still in the stub 10' of the siding, the rails of which have electrical connection with the corresponding rails of the main track), the track relay for block C is deenergized, its armature stands connected with the back 65 contact, and so the main cab circuit includes

in it the track resistance 26 as shown by the heavy line circuit. This circuit may be traced as follows: generator 33, series field 35, 36, 31, continuous rail connections to track circuit wire 17, armature switch 16', 70 resistance 26, wire 24, caution-control contact 20', whereon the insulated wheel 32 of the cab rests, wire 37, branch 39, relay 41, armature 41', connection 44 to the remaining terminal of the generator 33. Under these conditions, with the track resistance included in the main circuit in series with the field winding 35 of the generator, caution magnet 41 is effectively deenergized and its armature 75 is retracted, consequently breaking the signaling circuit for the "clear" lamp 50 at 41', and closing a circuit for the "caution" lamp 51 as follows: generator, common wire 53, caution lamp 51, connections 58, 56', 58', armature 41', connections 44 to generator. 85 Under these conditions, since the magnet 40 remains energized, and its front contacts are closed, brake magnet 54 and its parallel magnet 56 remain energized, so that there is 90 no automatic application of brakes. 90

The second east bound train shows the "danger" signal, owing to the presence of the first east bound train in the block ahead. Its insulated wheel 32 stands in connection with a "danger" contact 20' that now has no 95 connection with the continuous rail 11 on which connector 31 stands, owing to the opening of the armature switch connection, 16'-23, at the relay for a block ahead. Consequently the main cab circuit heretofore described stands completely deenergized, both magnets 40 and 41 having dropped their armatures, so that the brake magnet also has become deenergized and the brakes have automatically set. Under these conditions the 100 red lamp glows, its circuit being established, via the generator, 53, 52, 59, 40', 43, generator, the circuit for the clear lamp 50 being broken at the armature switch 41' and the circuit for the caution lamp 51 being broken 110 at the armature switch 56'. 110

The engineer may have to run the train, notwithstanding the danger signal, manually superseding the automatic operation of the brake-controlling magnet 54. This he 115 may do by depressing proceed switch 61, establishing for the brake magnet 54 a circuit 33, 53, 54, 55, proceed switch tongue 61, lower contact, 60, 43, 33 so that the brake-magnet armature is again attracted. 120

While I have herein described in some detail a specific embodiment of my invention it will be apparent to those skilled in the art that many changes of structure and arrangement may be made without departure 125 from the principles of my invention within the scope of the appended claims.

Having described my invention, what I claim is:

1. In a block signal system, the combina- 130

tion of a track having a rail divided into block sections insulated from each other and a rail electrically continuous from block to block, one said rail including, within each 5 block-area, insulated "danger" and "caution" rail-contacts, each spanned by a bond uniting the flanking major portions of the rail, means normally establishing low resistance electrical connection between the 10 "danger" and "caution" contacts respectively and the continuous rail, a resistance for each "caution" contact normally excluded from the connection of said contact with the continuous rail, automatic means 15 for each block, responsive to predetermined conditions, for opening the connection of the danger contact of a foreign block with the continuous rail and to include the resistance for a caution contact of a foreign 20 block in its stated connection with the continuous rail, and cab-signaling means comprising cab-carried circuit connections governed by the rail contacts and the varying 25 electrical relations of the latter to the continuous rail; a generator having two field windings, the said cab-carried circuit including one field winding, electroresponsive signal-controlling means differently responsive to higher voltage current, to lower voltage current and to current cessation, and a 30 circuit including the electro-responsive signal controlling means and the other field winding.

2. In a double-track block signal system, 35 the combination with two traffic tracks each comprising a rail divided into block sections insulated from each other and a rail electrically continuous from block to block, one of said rails including within the area of each 40 block a plurality of rail contacts insulated from the general rail and constituting respectively "danger" and "caution" contacts, each said contact spanned by an electrical conductor uniting the contiguous portion of 45 the general rail; a track circuit for each block including the general portions of two rails and the contact-spanning conductors, a source of current supply, and a relay-coil; means to establish low resistance connection 50 or to open the connection between the "danger" contact of some other block and the continuous rail controlled by the relay of each block, means for establishing low resistance connection or high resistance connection 55 between the continuous rail and two "caution" contacts, one in the next block, the other in a more remote block; controlled by the track relay of each block; and cab-signaling means comprising a generator 60 having a high-resistance shunt field winding and a series field winding, circuit connections for said series field winding including wheel contacts for co-operating with the "danger" and "caution" track-contacts, electro-responsive devices in said cab circuit 65

differently responsive to the low resistance, high resistance and open circuit conditions effected between the track contacts and the continuous rail, and signal devices governed by said electro-responsive devices.

3. In a block signal system the combination of a traffic track comprising a rail divided into block sections insulated from each other, a rail extending electrically-continuously from block to block, fixed contacts appurtenant to said continuous rail and including, within each block area, "danger" and "caution" contacts, means normally establishing low resistance electrical connection between each said contacts and the continuous rail, a resistance for each caution contact normally excluded from the connection of said contact with the continuous rail, electrical means associated with each block, comprising a relay bridging the rails, and a source of current supply for the block likewise bridging the rails, said relay controlling the connections for the "danger" contacts and "caution" contacts of foreign blocks and operable, when the relay is effectively deenergized, to open the appurtenant "danger" contact connection and include the resistance for a "caution" contact in the connection of said contact with the continuous rail, and cab signaling means comprising a generator having two field windings, circuit connections governed by connection of "danger" or "caution" contacts and the continuous rail, said circuit connections including one of said field windings and electro-responsive devices differently responsive to low resistance connection, higher resistance connection, and disconnection, respectively, of any said contact with the continuous rail.

4. In a block signal system the combination of cab carried devices comprising a generator having two field windings, signal devices affording a circuit for one said winding, main circuit connections from said generator to traveling contact devices including the other said winding, electro-responsive means in said main-circuit that are differently responsive to low resistance connection, higher resistance connection, and open circuit conditions, between said traveling contacts; and associated track apparatus comprising contact-portions for respective co-operation with the said traveling contacts of the cab, and automatic means for establishing low resistance connection, higher resistance connection, or open circuit conditions as between said contact-portions.

5. In a block signal system the combination of a traffic track comprising a rail divided into block sections insulated from each other, a rail electrically continuous from block to block including within each block area insulated "danger" and "caution" rail contacts, each spanned by a bond

uniting the contiguous portions of the rail, means normally establishing low resistance electrical connection between each "danger" contact and "caution" contact and the continuous rail, a resistance for each caution contact normally excluded from its said connection with the continuous rail, a track circuit for each home block, including a source of current supply, the blocked rail, a portion 5 of the continuous rail and the winding of a relay, said relay controlling the connection of danger and caution contacts of some foreign block with the continuous rail and operating when deenergized to break the connection of the appurtenant danger contacts with said continuous rail and to include the resistance for a caution contact in its connection with the continuous rail; and cab signaling means comprising a dynamo generator having two field windings, one in shunt and the other included in the main cab circuit, said main cab circuit comprising 10 connections governed by the rail contacts and also electro-responsive devices differently responsive to low resistance connection, higher resistance connection and disconnection of said contacts with respect to 15 said continuous rail, brake controlling means and signaling means, both governed by said electro-responsive devices.

20 25 30 35 40 45 50 55 60 65 70 75 80 85 90

2. In a block signal system the combination of a traffic track comprising a rail divided into block sections insulated from each other, a rail electrically continuous from block to block including within each block area insulated "danger" and "caution" rail contacts, each spanned by a bond uniting the contiguous portions of the rail, means normally establishing low resistance electrical connection between each "danger" contact and "caution" contact and the continuous rail, a resistance for each caution contact normally excluded from its said connection with the continuous rail, a track circuit for each home block, including a source of current supply, the blocked rail, a portion of

the continuous rail and the winding of a relay, said relay controlling the connection of danger and caution contacts of some foreign block with the continuous rail and operating when deenergized to break the connection of the appurtenant danger contacts with said continuous rail and to include the resistance for a caution contact in its connection with the continuous rail; and cab signaling means comprising a dynamo generator having two field windings, one in shunt and the other included in the main cab circuit, said main cab circuit comprising 65 connections governed by the rail contacts and also electro-responsive devices differently responsive to low resistance connection, higher resistance connection and disconnection of said contacts with respect to 70 said continuous rail, brake controlling means and signaling means, both governed by said electro-responsive devices.

3. In a block signal system, the combination of cab-carried devices comprising a source of current supply having two windings, signal devices affording a circuit for one said winding, main circuit connections from said source of current supply to traveling contact devices including the other said winding, and electro-responsive means in said main circuit that are differently responsive to low resistance connection, higher resistance connection, and open circuit conditions, between said traveling contacts.

4. In the cab-circuit of a block signal system, the combination of a generator, a main circuit, parallel "danger" and "caution" relays arranged to release their armatures under different voltage-conditions, an auxiliary relay controlled by the danger relay, and three signal circuits, two controlled by the respective danger and caution relays and the third controlled jointly by the caution and auxiliary relays.

In testimony whereof I hereunto set my hand.

YORKE BURGESS.
